(57) **CLAIM**

The ornamental design for a lid assembly for a fluid container of a sprayer, as shown and described.

DESCRIPTION

FIG. 1 is a perspective view of a lid assembly for a fluid container of a sprayer showing my new design;

FIG. 2 is a back elevational view showing the lid assembly for the fluid container of the sprayer of FIG. 1;

FIG. 3 is a front elevational view showing the lid assembly for the fluid container of the sprayer of FIG. 1;

FIG. 4 is a left side elevational view showing the lid assembly for the fluid container of the sprayer of FIG. 1;

FIG. 5 is a right side elevational view showing the lid assembly for the fluid container of the sprayer of FIG. 1; and,

FIG. 6 is a top elevational view showing the lid assembly for the fluid container of the sprayer of FIG. 1.

In FIGS. 1-6, the broken lines showing of the container, the inlet coupling, and the outlet structure is for illustrative purposes only and forms no part of the claimed design.
